ENDLESS MOP BELT TYPE FLOOR MOPPING MACHINE

John N. Georgas, Corsicana, Tex.

Application October 11, 1946, Serial No. 702,672

1 Claim. (Cl. 15—99)

1

The invention relates to a power driven floor mopping and polishing device.

An object of the invention is to provide a mopping machine in which the endless mopping element is designed to effect positive cleaning or polishing of the floor.

A further object is to provide a mopping machine wherein the endless mopping element is supplied with driving elements so positioned on the machine that the mopping element moves smoothly around its rollers and does not jerk or hang.

A still further object is to provide a mopping machine designed so that the operator may regulate the amount of friction, or force exerted, against the surface being cleaned.

With these objects in view, other objects and advantages will become apparent from a consideration of the following description and drawing wherein the drawing is a diagrammatic view of the device with the main casing and tank shown in section, the mop rollers being arranged coaxially with the drive pulleys in the manner illustrated at the front upper pulley.

The machine is shown as enclosed in a housing 2 with a handle 3 projecting upwardly therefrom. A liquid container 4 is mounted therein and carries liquid 5 through which the endless mopping belt 7 passes. A roller 8, preferably made of non-floatable material, is immersed in the liquid to take up slack existing in the belt 7. A frame 9 extending longitudinally of the roller has brushes 10 mounted thereon to remove dirt and other particles from the belt 7 as it passes through the solution 5.

A series of rollers 6 driven by belt 11 mounted at the forward end of the housing, serve as driving contact members for presenting a portion of the mopping belt, designated as the surface 20, to the surface being cleaned. It is to be noted that all five of the rollers adjacent the surface 20 are driven by the belt 11. This arrangement supplies driving action to the belt over the total length of the contact surface 20 thereby tending to prevent stalling or binding of the belt as it contacts the surface being cleaned. The number of rollers 6 may be increased so as to present a larger surface 20, or they may be decreased in numbers, thereby decreasing the surface area 20.

A power unit 13 mounted rearwardly of the liquid container is attached through speed reducer 14 to endless driving belt 15. V-notch pulleys 16 mounted near the upper portion of the liquid container and outside thereof, and similar pulley 16 mounted adjacent the series of roll-

ers 6 serve as drive members for the rollers 21 upon which the endless belt 7 moves. By this arrangement, the endless mopping belt 7 is driven at more than one point throughout its length which gives a smoother driving motion to the belt and prevents it from jerking or becoming stalled.

Wheels 18 mounted on the container 4 are used to regulate the amount of frictional contact between the belt surface 20 and the surface being cleaned immediately therebeneath by pivoting the machine on this roller as an axis. Wheels 18 may also serve as a means to move the mopping machine from one location to another by tilting the handle 3 rearwardly so as to lift the surface 20 of the belt 7 off the surface being cleaned.

Roller 22 adjacent the rear upper roller 21 is mounted on an arm 24, such arm being pivoted at 23 to the container 4, and extending through a slot (not shown) in the rear portion of the housing. A foot pedal 25 mounted on the exposed portion of arm 24 is arranged to engage toothed member 26 so that roller 22 may be positioned inwardly against the belt 7 and corresponding roller 21 to wring, or extrude, excess liquid from belt 7. It is to be noted that the path of the belt 7 is such that any excess squeezed from the belt falls back into container 4. The operator may therefore regulate the amount of liquid removed from the belt 7, depending upon the type of surface being cleaned and the type of cleaning and polishing solution being used.

A pipe 28 connected at 29 in the bottom of the container 4 extends upwardly through the pump (not shown) driven by motor 13, and up through the handle 3 to a liquid supply source (not shown). A drain plug 30, in the elbow 31 of the pipe 28 is also provided and may be used to drain the contents 5 from the container 4. It seems obvious that pipe 28 in conjunction with the pump may serve to fill container 4.

A cover plate 32 secured on the top of the housing 2 by suitable means such as bolts 33 provides access to the interior of the device for filling container 4 or for making minor adjustments on the device.

In operation of the device embodying the invention, the operator fills container 4, either by removal of cover plate 32, or by pipe 28 and the pump. The motor is then disengaged from the pump, and the operator moves handle 3 forward slightly so as to contact the surface 20 of the belt with the surface being cleaned. The operator may vary the frictional contact of the belt with the surface being cleaned by pivoting the machine on the wheels 18.

Broadly the invention contemplates a mopping machine wherein a constant pull is exerted on the mopping belt at spaced intervals so as to effect a smooth travelling motion of the continuous belt in combination with a machine wherein the friction of the belt with the surface being cleaned may be regulated as desired by the operator.

The invention claimed is:

A floor washing and drying device comprising, 10 a housing, a handle thereon, a liquid container mounted therein, an endless belt mop including an upper run for passing through the container to contact the liquid, a forward run travelling between the housing and container, a bottom run to travel along the floor and a rear run to travel between the housing and the container, a slack take-up roller immersed in the liquid container for bearing against the upper run of said endless belt, a series of rollers with an endless belt thereon mounted beneath the container for the bottom run of belt to pass beneath as it contacts the floor, a wheel rearward of said series of rollers mounted on said housing approximately midway between the front and rear run of said mop so that the device is tiltable about said roller thereby regulating the pressure exerted by the bottom run of said belt against the floor, a motor mounted in said housing, a plurality of mop belt rollers disposed to rollably support said upper, forward,

bottom, and rear runs of said endless mop, drive pulleys drivingly connected to at least some of said mop belt rollers, a speed reducer driven by said motor, an endless driving belt contacting said drive pulleys and said speed reducer for driving said endless mop, and squeeze means including a squeeze member pivotally mounted on said container adjacent a portion of said endless belt mop as it emerges from said container, said squeeze means including an elongated arm extending to the exterior of said housing and adjustable by the foot of the operator to move said squeeze member into compressive engagement with said portion whereby to squeeze excess liquid therefrom.
